LOUIS H. VON OHLSEN, OF NEW HAVEN, CONNECTICUT, ASSIGNOR TO THE SAFETY CAR HEATING & LIGHTING COMPANY, A CORPORATION OF NEW JERSEY

AUTOMATIC TRAIN CONTROL

Application filed February 4, 1929. Serial No. 337,222.

This invention relates to train control systems and more particularly to equipment of this character wherein the movement of a railway locomotive, car, or train, or other vehicle, is automatically controlled in accordance with the traffic condition of the track in advance of the train.

One of the objects of this invention is to provide a practical and effective railway signal and control system of simple construction and maximum reliability of operation. Another object is to provide an efficient signal system of the character described for automatically indicating in a moving vehicle the condition of the track in advance thereof and for automatically controlling the movement of the vehicle in response to such condition. Another object is to provide a cab-signalling and train-control system of the above-mentioned nature in which reliable communication may be established between devices along the track and cooperative devices upon the train or vehicle, inductively, and without the use of contact collectors or other sliding or rotating devices. Another object thereof is to provide for positive and reliable operation of the signal and control devices irrespective of local disturbances, such as disturbances in the vehicle-carried circuit or circuits, and, more particularly, irrespective of conditions effecting fluctuations and changes in the train receiving circuit due to fluctuations at or in the source of electrical potential from which the circuit derives, normally, its energizing current. Another object is to provide a simple, practical and reliable system of the above nature wherein the vehicle-carried circuit or circuits or parts thereof may be safely supplied with energy from sources that, for example, supply also motive energy to electrical driving equipment, electrical auxiliaries, remote control systems, and the like. A further object is to provide a system of the above-mentioned nature, the regular and safe operation of which will not be detrimentally affected by fluctuations and variations in the source of energy therefor or in the output of the source due to the association of such source with the regular or other electric train equipment. An-

other object is to provide a system in which current changes in a relay system, determined by track conditions, serve to actuate train-controlling or signalling devices, which will be protected against actuation of said devices by changes in the energizing current of the relay system brought about by causes other than the condition of the track in advance. Other objects will be in part obvious or in part pointed out hereinafter.

The invention accordingly consists in the features of construction, combinations of elements and arrangements of parts which will be exemplified in the structure to be herein-after described and the scope of the application of which will be indicated in the following claims.

In the accompanying drawing, in which is shown one or more of various possible embodiments of my invention,

Figure 1 shows diagrammatically a train-signalling and control system embodying a preferred form of my invention; and

Fig. 2 is a similar diagrammatic sketch illustrating a modified form of my invention.

Similar reference characters refer to similar parts throughout both views of the drawing.

Referring now to the drawing, it is first to be noted that, for the sake of greater simplicity of illustration, certain parts of the system or apparatus are either diagrammatically indicated or are omitted since they may take any suitable or appropriate form and since the details thereof do not form any part of this invention. For example, there is shown a relay 10 suitably related to the roadbed and track circuit and actuated or controlled by suitable circuits, relays, or the like, in accordance with the condition of the track in advance of the moving vehicle, and the relay itself may, in any suitable manner, coact in effecting or controlling other or related circuits. Since the details of the circuits associated with the relay 10 form no part of this invention, such circuits are not illustrated.

Associated with the roadbed and preferably positioned adjacent or in between the rails is an electromagnetic device generally

indicated at 11; this device comprises an iron core 12 and a winding 13 about the core 12, the winding 13 being controlled, as at the switch member 14, by the relay 10. It will be understood that any suitable number of suitably spaced devices 11 are associated with the roadbed or track rails, in accordance, for example, with the number and length of the blocks or rail sections. The remaining apparatus shown in Fig. 1 is carried by the vehicle and includes a device generally indicated at 15, adapted, as the vehicle moves along, to coact with the fixed device 11 associated with the roadbed. The device 15 includes an iron core 16 provided with certain energizing windings. These windings may be energized from any suitable source but, as illustrative of certain of the difficulties which my invention overcomes, the windings are supplied with energy from a generator 17 mounted upon the vehicle with which is associated a storage battery 18 connected in circuit 1. The generator 17 is driven by a motor 19 which receives its energy from, for example, the transmission circuit which supplies the vehicle with electric motive power. The generator 17 supplies energy, preferably at much less voltage than the voltage of the transmission line, to any appropriate auxiliary devices, such as train control circuits, lamp circuits, signalling devices, etc., and to insure the supply of energy to such devices during periods when the generator 17 is not operating, the generator 17 maintains in substantially charged condition the storage battery 18. Any suitable automatic switch, indicated at 20, may be provided to automatically connect and disconnect the generator and storage battery. In the present embodiment a lamp circuit is indicated at 2 in the drawing, and a train signalling or control circuit is indicated by a legend.

In certain preferred forms of installation, the motor 19 is constructed and designed to start, without starting transformers or resistances, immediately upon the line voltage being impressed thereon, and in any event the motor is started and stopped in accordance with the supply or interruption of power in the transmission line. The starting of the motor 19 under such circumstances often times takes place frequently and is so instantaneous that the generator 17 builds up so rapidly as to cause a substantial surge in potential and current in its output. While such surges may not be harmful with respect to certain of the devices supplied with energy by the generator, yet it has been found that such fluctuation, surge, or the like, has been the cause of actuating the train signal and control circuits irrespective of the condition of the track in advance. A dominant aim of this invention is to prevent such im-

proper actuation of the train signal and control circuits.

Now, referring to Fig. 1 of the drawing for a more detailed understanding of the present control system, the electromagnetic device 15, which may be called a receiver, is carried by some part of a locomotive or other railway vehicle in a suspended position over the roadbed or track. At predetermined positions along said roadbed, the track members or inductors 11 are secured in such position as to come within the magnetic field of the receiver as the train passes along the track, in such a manner as to shorten the air gap in said field and decrease the reluctance thereof.

The normally shorted winding 13 on the inductor member is connected by means of the relay 10 to track circuits, not shown, in such a way as to be open-circuited should traffic conditions in advance of the train be such as to establish the conditions under which the train control mechanism aboard the train is to come into operation. The magnetic core 16 is provided with a pair of divergent pole pieces thrust downwardly toward the track inductor, the core being of a modified horse-shoe shape. On one leg of the core is a primary winding 21 connected to the storage battery by means of circuit 3, and on the other leg of said magnetic core is a secondary winding 22, which forms part of a circuit 4, connected in parallel with said primary circuit 3, as shown. In series with said secondary winding 22 in said circuit 4 is a relay 23, which is normally energized by the current in circuit 4 to keep said circuit closed.

Before describing other features shown in the drawing, the normal operation of the devices already described will be explained. With the train running freely on an open signal, the primary coil 21 of the receiver receives a substantially constant direct current from the storage battery, and at the same time the relay 23 is energized by its connection to the storage battery to maintain the relay circuit 4 in closed condition. Now, should the train pass over a section of track so as to bring the receiver 15 in juxtaposition to one of said track inductors 11, and should the conditions obtaining in the track in advance of the train be such as to give a clear signal, the track relay shown in the drawing at 10 would maintain closed the circuit through the winding 13 upon said inductor. If, however, traffic conditions should be such as to set a stop or other warning signal, the relay 10 would trip and open-circuit the winding 13, and, as the inductor passes under the poles of the receiver, the air gap in the magnetic field of said receiver being suddenly shortened and the reluctance of the magnetic circuit reduced thereby, a sudden increase in the magnetic flux through

the core 16 would take place and induce a single cycle of A. C. in the secondary winding 22, one half of which cycle is in opposition to the normal current flowing through the relay circuit. This opposing current, being of sufficient strength to trip the relay 23, would set in operation or control the operation of the signalling or control devices maintained in the train control circuits. If, however, the winding upon the track inductor be close-circuited, the changing flux through said inductor as the latter passes under the vehicle-carried receiver will build up a current in said closed circuit which will react upon said magnetic inductor to oppose the lines of force received from the magnetic circuit of the receiver 15, and as equilibrium will not be restored until the parts have been separated by the onward movement of the train, there will not be induced in the relay circuit 4 sufficient voltage to trip the relay 23 and actuate the train control circuit.

But it is to be noted that fluctuations at the source of direct current, in this case the storage battery 18, if of sufficient scope, will also serve to cause current changes in the primary 21 of the receiver 15 and induce in the secondary 22 thereof, waves of A. C. of which particular respective half-waves are opposed to the normal current in the relay circuit 4, which induced current may be of sufficient strength to permit the tripping of the relay 23 and produce activity in the train control circuits. This result is, of course, undesirable and to be avoided.

In Fig. 1, one way of preventing the accidental and unintended actuation of the train signal devices is disclosed. A transformer is associated with the vehicle-carried circuits 3 and 4 so as to have its primary winding 24 connected in series with the primary coil 21 of the receiver, while its secondary coil 25 is connected in series in the relay circuit 4. Resistances may be included in the two circuits, as indicated at 26 and 27, to control and regulate the current flowing through said circuits. With the transformer connected in the circuits 3 and 4, as described, should it happen that the generator be suddenly brought into charging relation with the storage battery or that a heavy load be suddenly thrown upon the storage battery, causing substantially instantaneous and wide fluctuations in its output voltage, the resultant rapid change in amperage of the current flowing through the primary winding 21 of the receiver would, obviously, induce momentarily a current in the relay circuit 4 in opposition to the relay energizing current therein, tending to trip the relay, but simultaneously with this effect the primary coil 24 of the transformer, through which passes the same current that passes through the primary of the receiver,

would be energized and a current induced in the secondary winding 25 of the transformer in a direction to oppose the current arising in the receiver secondary winding 22. By properly proportioning the transformer coils 24 and 25, the two currents induced in the relay circuit may be made to neutralize one another and prevent the potential change at the storage battery from tripping the relay 23.

In Fig. 2 is disclosed another way of connecting the transformer in relation to circuits 3 and 4 so as to effect the same results. In this case, the secondary 25 of the transformer is connected as before, in series with the relay 23 and receiver secondary winding 22. But in this instance the primary 24 of said transformer, and a resistance 26, are connected across the battery so as to be subjected directly to voltage changes across the battery 18. A change of potential at the battery tending to cause current changes in the relay circuit to trip the relay will, as described above, induce oppositely directed currents in the winding 25, to neutralize or balance out the current changes in the relay circuit, which tend to trip the relay.

From the foregoing, it will be seen that this invention is well adapted to attain the ends and objects thereof in a thoroughly practical and reliable manner; that few moving parts are employed which might get out of order and reduce the efficiency of the system; and that a train control system has been devised which may safely be used, with power taken from a convenient source, even though that source be subject to sudden and wide variations in the potential of its electrical output.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In an automatic train control system, in combination, a car movable along a track, a receiver mounted upon said car comprising an iron core and a primary and a secondary coil, a relay adapted to control the operation of translating devices on said car, a source of electrical potential, a receiver circuit connecting said primary coil with said source, a relay circuit connected to said source and including said secondary coil, and means associated with both of said circuits for neutralizing current effects produced in said relay circuit by sudden current changes in said primary coil due to potential fluctuations at the source.
2. In an automatic train control system,

in combination, a car movable along a track, a receiver mounted upon said car comprising an iron core and a primary and a secondary coil, a relay adapted to control the operation 5 of translating devices on said car, a source of electrical potential, a receiver circuit connecting said primary coil with said source, a relay shunt circuit connected to said source normally to hold said relay closed and including said secondary coil, and inductively coupled means associated with both of said circuits for neutralizing current effects produced in said relay circuit by sudden current changes in said primary coil due to potential 10 fluctuations at the source.

3. In an automatic train control system, in combination, a source of potential carried on a vehicle, a vehicle-carried circuit having therein a relay and connected to said source 20 both directly and inductively, and means for preventing actuation of said relay by induced current in said circuit caused by fluctuations at said source.

4. In an automatic train control system, in combination, a circuit including a source of potential and a relay, a second circuit including said source and having said relay coupled thereto, and means acting upon said first circuit to prevent current changes in said second circuit due to potential fluctuations at said source from actuating said relay.

5. In an automatic train control system, in combination, electro-responsive means including a vehicle-carried source of potential and two inductively coupled circuits connected in parallel to said source, one of said circuits including a relay, means associated with the track adapted inductively to coact with said electro-responsive means as the vehicle moves along the track to actuate said relay, a translation device carried by said vehicle and operatively responsive to the actuation of said relay, and means associated with both said circuits for neutralizing induced current effects in said relay circuit due to potential fluctuations at the source.

6. In an automatic train control system, in combination, a source of potential subject to fluctuations, two-train-carried inductively coupled circuits having associated therewith electro-responsive means energized by said source and responsive to track conditions, a relay associated with said circuits, and means for preventing fluctuations in said source of potential from actuating said relay comprising a transformer operatively associated with both of said circuits.

7. In an automatic train control system, in combination, a source of potential carried on a vehicle, a pair of inductively coupled circuits connected in parallel to said source, a relay in one of said circuits, and means for preventing fluctuations in said source of potential from actuating said relay comprising

ing a transformer having its secondary coil operatively associated with said relay-containing circuit and its primary coil operatively associated with the other of said circuits.

8. In an automatic train control system, 70 in combination, a source of potential carried on a vehicle, a train-controlling device in the vehicle, a vehicle-carried electromagnetic device suspended over the track, a relay, a circuit including said source and said electromagnetic device and said relay and controlling said vehicle-controlling device, a track inductor positioned to cut the field of said electromagnetic device as the vehicle passes, and inductive means associated with said relay-containing circuit for balancing out current effects induced by said electromagnetic device in said circuit through potential fluctuations at the source.

9. In an automatic train control system, 85 in combination, a storage battery and a battery charging generator carried on a vehicle, a circuit including said battery, said generator and a switch adapted to open and close said circuit, a train-controlling device in the vehicle, 90 a vehicle-carried electromagnetic device suspended over the track, a relay, a circuit including said storage battery and said electromagnetic device and said relay and controlling said vehicle-controlling device, a track 95 inductor positioned to cut the field of said electromagnetic device as the vehicle passes, and inductive means associated with said relay-containing circuit for balancing out current effects induced by said electromagnetic 100 device in said circuit through the opening and closing of said generator circuit.

10. In an automatic train control system, in combination, a vehicle-carried storage battery connected to be intermittently charged 105 by a generator, a train-controlling device on the vehicle, a relay, a vehicle-carried electromagnetic device suspended over the track and comprising a primary and a secondary coil, a transformer having a primary and a secondary coil, a circuit including said battery and both of said primary coils, a circuit including said battery, said relay and both of said secondary coils and adapted to control said train-controlling device, and a track inductor positioned in the path of travel of the field of said electromagnetic device.

11. In an automatic train control system, in combination, a source of direct current carried by a vehicle and subject to sudden 120 output voltage changes, a train-controlling device on the vehicle, a relay controlling said train-controlling device, a vehicle-carried electromagnetic device suspended over the track, a track inductor positioned in the path 125 of travel of the field of said electromagnetic device and adapted to actuate said relay in response to traffic conditions, said electromagnetic device comprising a pair of inductively coupled coils, a circuit including one 130

of said coils and said source, a circuit including the other of said coils, said relay and said source, and means comprising a primary coil connected with said first circuit to receive 5 current varying as the current in said first circuit varies under the influence of voltage changes at the source, and a secondary coil connected in said second circuit and inductively coupled with said primary coil to supply 10 a neutralizing current in said second circuit and prevent the actuation of said relay through current effects caused therein by the inductive influence of current changes in said first circuit upon said relay-containing circuit.

12. In an automatic train control system, in combination, a source of suddenly variable direct current carried by a vehicle, a discontinuous magnetic core carried by said vehicle having a primary winding connected to 20 said source and a secondary winding connected to said source and having its magnetic circuit included in the magnetic circuit of said primary winding, a relay in the circuit of said secondary winding, means positioned along the track in the path of travel of the magnetic field of said magnetic core and adapted under predetermined traffic conditions to induce current in said secondary winding to trip said relay, and inductive 25 means electrically connected with both of said windings adapted to prevent sudden variations at said source from tripping said relay.

13. In an automatic train control system, in combination, a source of suddenly variable direct current carried by a vehicle, a discontinuous magnetic core carried by said vehicle having a primary winding connected to 35 said source and a secondary winding connected to said source and having its magnetic circuit included in the magnetic circuit of said primary winding, a relay in the circuit of said secondary winding, means positioned along the track in the path of travel of the 40 magnetic field of said magnetic core and adapted under predetermined traffic conditions to induce current in said secondary winding to trip said relay, inductive means electrically connected with both of said 45 windings adapted to prevent sudden variation at said source from tripping said relay, said means comprising a coil connected in series relation with said primary winding and said source, and a coil inductively 50 coupled with said first coil and connected in series relation in said relay-containing circuit.

14. In an automatic train control system, in combination, a vehicle carrying a circuit 55 having included therein a relay and electro-responsive means and a storage battery for locally energizing said relay and said electro-responsive means; means associated with the track along which said vehicle runs adapted to affect said electro-responsive means in

accordance with the conditions of the track; a source of potential for charging said storage battery; an automatic switch for connecting said source to the battery when the condition of the former is appropriate for 70 charging the battery; and means for neutralizing fluctuations in the energizing current in said local circuit to prevent actuation of the relay in response to said fluctuations.

15. In an automatic train control system, in combination, a vehicle carrying a storage battery having connected thereto two circuits, one of said circuits including a relay and a winding, the other of said circuits including a winding; a common core for said windings, said core being positioned to be affected by means positioned along the track; a source of potential for charging said storage battery; and means causing a fluctuation in local energizing current in one circuit to neutralize the effect of fluctuation in local energizing current in the other circuit.

16. In an automatic train control system, in combination, a vehicle carrying a storage battery having connected thereto two circuits, one of said circuits including a relay and a winding, the other of said circuits including a winding; a common core for said windings, said core being positioned to be affected by means positioned along the track; 90 a source of potential for charging said storage battery; and inductively related windings, one in each of said circuits, for neutralizing in the latter the effects of fluctuations in local energizing current.

17. In an automatic train control system, in combination, a source of electrical energy subject to fluctuations, a magnetic core, a plurality of windings about said core and connected to said source, and a relay directly interposed between one of said windings and said source and inductively interposed between another of said windings and said source.

18. In an automatic train control system, in combination, a source of electrical energy subject to fluctuations, a magnetic core, a plurality of windings about said core and connected to said source, a relay connected to said windings, an inductance interposed between one of said windings and said source, and a second inductance coupled with said first mentioned inductance interposed between another of said windings and said source whereby fluctuations of said source tending to operate said relay are neutralized by said coupled inductances.

19. In an automatic train control system including a vehicle and a track, in combination, a source of potential subject to fluctuations, a magnetic circuit mounted on said vehicle whose reluctance is made to change in accordance with the movement of said vehicle over a cooperating control on said track, means connected to said source operated by 125 130

the variation in the reluctance of said magnetic circuit, and inductively coupled means preventing variations in said source from actuating said first mentioned means but permitting free actuation due to the variation in the reluctance of said magnetic circuit.

In testimony whereof, I have signed my name to this specification this 18th day of January, 1929.
